[57] CLAIM

The ornamental design for a roadway light for vehicles, shown and described.

DESCRIPTION

FIG. 1 is a left side elevational view of a roadway light for vehicles showing may new design, with the opposite side being a mirror image;

FIG. 2 is a reduced front elevational view thereof, with the broken line showing for illustrative purposes only and forming no part of the claimed design;

FIG. 3 is a rear elevational view thereof; and,

FIG. 4 is an enlarge perspective view thereof.

Any broken line, illustration contained within the drawing disclosure is for illustrative purposes only, and is not a part of the design sought to be patented.
